UNITED STATES PATENT OFFICE

OTTO BEHIMER, CHICAGO, ILLINOIS, ASSIGNOR TO THE TEXAS COMPANY, OF NEW YORK, N. Y., A CORPORATION OF DELAWARE

FRACTIONATING METHOD

Application filed February 10, 1928. Serial No. 253,258.

The invention relates primarily to improvements in the methods employed for the handling of vapors of oil which have been generated in a still or the like and more particularly it has reference to the separation or fractionation of such vapors under pressure.

In the distillation or cracking of oils, fractionating columns or towers are now commonly employed for the purpose of separating the various constituents of the vapors generated, and these towers are usually so constructed as to permit the vapors which are introduced at the bottom to follow a tortuous path towards the top of the column. For the purpose of diverting the vapors in their passage through the tower, the latter may be filled with rock or other suitable material, or it may be provided with a series 20 of bubble trays which carry layers of oil through which the vapors are forced to pass.

In one common form of tower, the trays are provided with tubular openings which are covered by suitable caps that serve to divert the vapors and force them downwardly through the layers of oil within the trays. A portion of the vapors will be condensed in passing through the tower but if no means were provided to aid in cooling the latter, its temperature would soon be raised to such a point that heavy, undesirable constituents would be carried through and into the final condenser. In order to maintain the proper temperature within the tower, cooler oil is usually introduced at the top and allowed to gravitate toward the bottom through suitable vent pipes arranged at a desired overflow level within each of the trays. This cooler oil has in the past been supplied largely from reflux condensers which have been placed in the vapor line leading from the tower and which have been cooled by air or any other suitable means to cause a return of a portion of the vapors in the form of reflux condensate. It has also been proposed in the past to pump gasoline or other light constituents of oil from storage into the top of the tower to supply the desired cooling effect.

In accordance with the present invention

it is contemplated to pump the gasoline or other final condensate into the top of the tower but in lieu of taking this refluxing material from storage, it is proposed to take it from some point in the system at which the pressure is substantially the same as that maintained on the tower itself. This point may either be at some intermediate location in the coil of the final condenser or it may be beyond the latter but in advance of the point at which the pressure is released by the control valves on an accumulator drum connected with the condenser.

A number of advantages arise from the particular mode of operating the system contemplated by the present invention, among which is an important advantage arising from the fact that in introducing the refluxing material into the top of the tower, it is not necessary to buck the entire pressure within the latter. All that is required is to compensate for the small drop in pressure through the vapor line and the coil of the condenser and to produce a slight additional pressure which is sufficient to lift the gasoline to the top of the tower. For this purpose it has been found that a centrifugal pump is very satisfactory and the latter may very readily be packed in a suitable way to prevent leakage of the gases. On the other hand, where an attempt is made to supply the refluxing material from storage, considerable difficulty is encountered in the use of the high pressure pumps by way of leakage around the packing, etc.

Another advantage derived by the use of the present invention is that the gasoline or other condensate which is returned to the tower does not have time to go off color when it is returned from a point within or immediately beyond the final condenser. Whenever gasoline from storage is relied upon for the refluxing medium, some difficulty is frequently experienced with the color of the final product. With these and other incidental objects and advantages in view, the invention will now be described in detail with reference to the accompanying drawing in which:

Figure 1 is a diagrammatic showing of a

system illustrating or embodying the present invention and—

Figure 2 is a similar view of a modification.

Referring now to Figure 1, it will be noted that there is provided a separating tower or fractionating column 10, which, for the sake of illustration, has been shown as of the bubble tower type. Vapors may be introduced into the tower at a point near the bottom by means of an inlet pipe 11 which may serve to convey the products of distillation from a still or battery of stills or from any similar source. The vapors so introduced will preferably be under superatmospheric pressure and they will rise within the tower toward the top. In the course of their passage through the tower they will be diverted by suitable means provided in connection with the trays 12. Since the details of the interior construction of the tower do not form a part of the present invention, no further description of the same is believed to be necessary. A portion of the vapors in passing through the tower will be condensed and will remain in the trays or will be passed successively to the next lower tray by means of suitable overflow vent pipes. Those portions of the vapors which remain in the vapor state on reaching the top of the tower will be conveyed by means of the vapor line 13 into the coil 14 of the final condenser. The latter will preferably be cooled by means of water or other suitable medium which is passed continuously through the containing vessel surrounding the coil.

At an intermediate point, the tubes which go to make up the condenser coil may be extended through the containing vessel and into a suitable separator. Thus, the mixed vapors and oil may be led through a tube 15 of the condenser coil into the drum of a separator 16. Another tube 17 of the coil leading from the separator will then serve to convey a portion of the mixed vapors and oil to the balance of the coil and from the latter into an accumulator drum 18 and a storage tank 19. However, another portion of the mixed vapors and oil passing through the separator or trap 16 will be passed through a secondary outlet 20 and into a separate coil 21, which may, if desired, be located within the cooling medium in the containing vessel of the condenser. In this coil the vapors may be fully condensed and the condensate, which is still under a pressure substantially equal to that maintained on the tower itself, may be passed through a centrifugal pump 22 and returned by means of the pipe line 23 to the top of the tower. Before entering the tower, the line 23 is preferably divided into two branches which are provided with valves 24 and 25. By proper adjustment of these valves the refluxing medium may be introduced either above the uppermost tray or at

an intermediate point within the tower, as, for example, onto the fourth tray from the top. It will be apparent that all the centrifugal pump is called upon to do is to compensate for the small drop in pressure 70 through the vapor line 13, the condenser coil 14, trap 16 and coil 21, and in addition, to lift the liquid condensate to the top of the tower. This is a comparatively light pressure burden, which the centrifugal pump is 75 readily capable of assuming. The usual packing difficulties encountered in the high pressure types of pumps, which give rise to considerable leakage, are thus avoided.

As shown in the drawing, the bottom of the tower 10 may, if desired, be provided with a coil 26 through which the fresh charge of oil may be led prior to its introduction into the still which constitutes the source of the vapors arriving through the inlet pipe 11. The coil 26 will thus bring the fresh charge into heat exchange relation with the heated vapors and will tend to cool the latter at the same time that the charge is raised in temperature. This coil may, if desired, be located at the top of the tower or at an intermediate point.

In Figure 2 there is illustrated a slight modification of the system disclosed in Figure 1. As here illustrated, it is possible to locate the separator or trap, which serves to divert a portion of the condensate, at a point between the condensing coil and the accumulator drum, since it is contemplated that the pressure on the system will be maintained to a point beyond this drum. As shown in this figure, the condenser coil 141 may be of the usual type and may terminate in an outlet pipe 151 leading into the drum 161 of a separator or trap. A portion of the condensate passing through this trap may then be led through an outlet pipe 171 into an accumulator drum 181 and then into the storage tank 191. Another portion of the condensate may be led through a pipe 201 into a centrifugal pump 221 which may serve to return the refluxing material to the top of the tower. Suitable valves may, as in the system illustrated in Figure 1, serve to control the introduction of the refluxing medium on to the top tray or at an intermediate point.

While the invention has been disclosed in connection with a fractionating column of the bubble tower type, it should be understood that it is equally applicable to a fractionating system employing a rock tower or other similar column. Many changes may be made in the form and arrangement of the apparatus employed without departing from the spirit of the invention and it is desired to be limited only by the scope of the claim which follows.

What I claim is:

A process of fractionating vapors of hydrocarbon oils which comprises subjecting the

vapors to fractionation under superatmospheric pressure in a fractionating zone, cooling vapors from said zone to produce partial condensation, separating the resulting combined vapors and condensate into two streams, subjecting one stream to further cooling and, prior to any substantial pressure reduction, returning the resulting condensate to said fractionating zone as a refluxing medium, and subjecting the other stream to further cooling to produce a final desired distillate.
